United States Patent Office.

JOHN W. SCHREIBER, OF NEW YORK, N. Y.

Letters Patent No. 79,014, dated June 16, 1868.

IMPROVEMENT IN LAMP-BURNERS.

The Schedule referred to in these Letters Patent and making part of the same.

TO ALL WHOM IT MAY CONCERN:

Be it known that I, JOHN W. SCHREIBER, of New York, in the county of New York, and State of New York, have invented a new and useful Improvement in Lamp-Burners; and I do hereby declare that the following is a full, clear, and exact description thereof, which will enable others skilled in the art to make and use the same, reference being had to the accompanying drawings forming part of this specification, in which—

Figure 1 represents a vertical transverse section of my improved lamp-burner.

Figure 2 is a vertical longitudinal section of the same.

Similar letters of reference indicate like parts.

This invention relates to a new burner for coal-oil and other lamps, its object being to cause the complete combustion of all the oil elevated by the wick.

The invention consists, first, in supporting the lamp-chimney on lugs or springs that project from the solid base of the burner, so that an open space is left below the lower edge of the chimney for the air to pass to the outside of the flame.

The invention consists, second, in the use of an outer wick-tube, which reaches above the upper end of the main wick-tube, and which rests upon springs, that hold it as high up as possible, so that a horizontal circular plate projecting from it is held against a contracted portion of the chimney.

The invention also consists in hinging the cap of the burner to the aforesaid circular plate, or to the plate upon which it rests, so that it can be folded back to facilitate the lighting of the lamp.

The invention finally consists in so shaping the cap that it will, although it has a circular base, not be conical, but with flat sides, so that the air is more equally conducted to the flame.

A, in the drawing, represents the body or dead-air chamber of a lamp-burner.

B is the main wick-tube arranged therein.

C is the upper plate of the body, and the base-plate of the upper appendage of the same.

The plate C projects from the sides of the body, as shown, and is not perforated, except where the wick-tube passes through it.

D represents a secondary wick-tube. The same is fitted around the upper portion of the main tube B, and projects above the same, as is clearly shown in the drawing.

From the tube D projects a perforated plate, E, between which, and the base-plate, springs *a a* are arranged, that serve to elevate the tube D, and its appendages, they forming the support of the same.

F F are spring-holders, attached to the plate C, and projecting upon and from the same. They are bent inward, as at *b* in fig. 2, or are otherwise provided each with a shoulder, *b*, to enable them to support the chimney above the plate C, thereby an open space is produced between the lower edge of the chimney and the plate C, for the air to pass in.

The chimneys to be used in connection with this burner are to have a contracted portion opposite the plate E, the said plate E being, by means of the springs *a*, held against the narrow part of the chimney, as is clearly shown in fig. 2, and, as not all chimneys are made exactly alike, the springs *a* will cause the plate E to adjust itself to chimneys in which the contracted portion is higher or lower.

G is the cap of the burner. The same is not of truly conical shape, but has its upper part narrow, parallel with the slot. Heretofore the caps were always made conical, and were therefore wider opposite the middle of the slot than they were opposite the ends of the same, and a larger supply of air was consequently brought to the middle of the flame than to the ends of the same. By making the upper part of the cap narrow, an equal supply of air will be brought to all parts of the flame.

The cap G is hinged to the plate E, as shown, to allow its being easily swung open, for the purpose of facilitating the lighting of the lamp.

From the plate C projects a rod, H, which serves to support and hold a reflector on the outside of the chimney, as indicated in figs. 1 and 2.

Having thus described my invention, I claim as new, and desire to secure by Letters Patent—

1. The secondary tube D, arranged around the main wick-tube B of a burner, and projecting above the same, when said secondary tube is, by means of springs $\alpha\alpha$, that fit under a plate, E, projecting from the tube, held up, and adjusted up and down, as set forth.

2. Closing the chimney of a lamp-burner, by means of a perforated plate, E, which is held up against a contracted portion of the chimney by means of springs $\alpha\alpha$, as described, so that all the air will have to pass to the flame through the said plate E.

3. A lamp-burner, consisting of the body A, tube B, and base-plate C, in combination with the secondary tube D, perforated plate E, springs α , cap G, and spring-holders F F, or their equivalents, all made and operating substantially as herein shown and described.

JOHN W. SCHREIBER.
